BOTTLED BEVERAGE MIXER

John M. Bettencourt, Yuba City, Calif.

Application March 28, 1939, Serial No. 264,545

5 Claims. (Cl. 259—54)

This invention relates to the soft drink bottling industry, in which various soft drink mixtures as they are bottled require mixing or agitating in the bottles, as is well known.

At present, such mixing is effected by shaking the bottles by hand, the operator usually holding two bottles (if of the standard small size) in each hand at one time. This is a hard and tiring job as will be realized, and is relatively slow.

The principal object of my invention is to eliminate this hand shaking operation by providing a machine designed to hold a case of bottles at a time, and arranged so that with practically no effort on the part of the operator, the contents of all the bottles of the case will be simultaneously and thoroughly agitated and mixed. Not only is a more uniform mixing action obtained than by the hand method now used, but a much larger output in a given time is possible with no increase in labor cost, since an entire case of 24 bottles per operator may be mixed in the same time that it now takes to mix 4 bottles.

Further, the work incident to placing the case and bottles in and removing the same from the machine is far less arduous and consumes less of the operator's time than with the hand shaking method, giving him more time to devote to other matters incident to the job.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

40. Figure 1 is a side elevation of the machine, in position to receive a case of bottles.

Figure 2 is a fragmentary longitudinal section of the machine, showing a case of bottles therein and engaged by the presser or hold down plate.

Figure 3 is a fragmentary rear or discharge end view of the machine.

Referring now more particularly to the characters of reference on the drawings, the machine 50 comprises a supporting frame which includes end standards 1 of suitable height and spaced apart a distance greater than the length of a standard bottle case C.

Extending between the standards at the top is 55 a case supporting platform 3, which includes lon-

gitudinally extending bars 4 which support a series of rollers 5 projecting above the bars and arranged in transversely spaced rows lengthwise of the platform. A central longitudinal shaft 6 is mounted lengthwise on and under the platform, being supported at its ends in journal boxes 7 on the top of standards 1, the bearing elements for the shaft being standard roller or other antifriction bearings.

A screw 8 is mounted on and depends from the platform centrally of its area or in radial alignment with shaft 6, and is additionally supported at its lower end by a brace unit 9 depending in converging relation to the screw from adjacent the ends of the platform. A weight 10 is axially 10 adjustable on the screw, being held at any desired point in the length thereof by lock nuts 11.

Mounted on and upstanding from the platform along the sides thereof are side walls 12 spaced apart a distance somewhat greater than the 20 width of case C and approximately the same height as said case and forming with the platform, a case receiving housing. Rollers 13, disposed with their axes vertical, project through the side walls adjacent their intake end for engagement with the sides of the case to centralize the same as it moves onto the platform from the adjacent end thereof; said rollers being mounted on spring straps 14 which allow them to yield laterally out. A supporting table 15 for a case, 30 and which includes rollers 16 on which the case rides, is mounted as a unit with the machine and extends ahead of the intake end of the platform on the level thereof when said platform is in its normal upright position; said table being 35 supported from the adjacent end standard 1.

Disposed between the side walls at the top thereof is a rigid presser plate 17 whose area is greater than that of the top of the case C. This plate is faced on its under side by flexible leather 18 of a size to enter the case, and which is backed by a layer of felt 19.

A transverse shaft 20, having a crank handle 21 at one end, is turnably mounted at its ends in brackets 22. These are disposed on the outside of the side walls centrally of their ends, and are movable vertically between guide bars 23 on said walls. Clamping bolts 24 between the brackets and walls maintain the brackets in any adjusted position.

The shaft extends over the presser plate, and is provided adjacent the side edges of said plate with eccentrics 25 turning in straps 26 secured on the presser plate; the eccentric being disposed relative to the handle so that when said eccen-

trics are uppermost, the handle extends upwardly also. The presser plate is unbalanced relative to the eccentrics, so that it will normally tilt upwardly somewhat toward the intake end of the machine, by a suitably disposed weight element 27 thereon.

In operation, a case C is placed on the table 15 and is there filled with bottles B, the case being left open on top as usual. The filled case is then 10 slid onto the platform 3 between the side walls, the head end of the case engaging the downwardly tilted presser plate and turning the same to a substantially level position. The brackets 22 are set so that the facing of the presser plate 15 then clears the top of the case sufficient to prevent any jamming or catching of the same as the case is slid into position.

The handle 21 is then turned down, which lowers the eccentrics and of course the pressure plate, so that the leather facing thereon enters 20 the case and is pressed into firm engagement with the caps of the bottles, as shown in Fig. 2, while the plate itself engages the rim of the case.

25 This done, the operator exerts a rotating pressure on the housing. Due to the weight 10, which is initially set on the screw 8 so as to substantially counterbalance the housing when loaded, and to the use of antifriction bearings for the 30 axial shaft 6 of the housing, the latter rotates very easily, and will continue to rotate without further rotative impulses being imparted thereto for the necessary length of time, if the initial impulse is sufficiently strong. This continuous 35 rotation of the case of course alternately inverts and rights the bottles, effectively mixing the contents thereof. While the mixing operation is in progress, the operator need pay no attention to the same, but can devote his time to 40 filling the next case.

When the rotation ceases, the housing will 45 stop right side up, and the operator then turns the handle 21 to release the presser plate. The case waiting on table 15 is then shoved into the housing, pushing the first case out and onto 50 the delivery conveyor D. This latter unit may be a standard feature of the bottling works equipment, the mixing machine, which is portable, being disposed so as to line up with one end of said conveyor.

55 From the foregoing description it will be readily seen that I have produced such a device as substantially fulfills the objects of the invention as set forth herein.

50 While this specification sets forth in detail the present and preferred construction of the device, still in practice such deviations from such detail may be resorted to as do not form a departure from the spirit of the invention, as defined by 60 the appended claims.

Having thus described my invention, what I claim as new and useful and desire to secure by Letters Patent is:

1. A bottle agitating machine comprising a platform to support a case of bottles and adapted to receive the case thereon from one end, a rigid presser plate over the platform to engage the top of the case, a transverse shaft above the plate rockably supporting the same at a point relative to the longitudinal distribution of weight 10 thereof such as to cause the plate to normally tilt upwardly toward the receiving end of the platform.

2. A bottle agitating machine comprising a platform to support a case of bottles and adapted to receive the case thereon from one end, a rigid presser plate over the platform to engage the top of the case, a horizontal shaft under and extending lengthwise of the platform, means mounting the platform on the shaft for rotation about the 15 axis thereof, standards supporting the shaft at the ends of the platform and case supporting tables aligned with the platform and supported at their end adjacent said platform by the 20 standards.

25 3. A bottle agitating machine comprising a platform to support a case of bottles and adapted to receive the case thereon from one end, a rigid presser plate over the platform to engage the top of the case, a horizontal shaft under and supporting the platform and about the axis of which the platform may rock, a rigid member mounted at its upper end in connection with and depending from the platform radially of the shaft, a counterweight on said member, and a brace unit depending from the platform and engaging the 30 lower end of the member.

35 4. A bottle agitating machine comprising a platform to support a case of bottles, and mounted for rotation about a horizontal axis, a presser plate over the platform to engage a case supported thereon, a transverse shaft extending over the plate intermediate its ends, means turnably supporting the shaft from the platform, means applied to the shaft at one end to rotate 40 the same, eccentrics on the shaft overhanging the platform and eccentric engaging straps fixed on the plate.

45 5. A bottle agitating machine comprising a platform to support a case of bottles, and mounted for rotation about a horizontal axis, a presser plate over the platform to engage a case supported thereon, a shaft extending over the plate, means turnably supporting the shaft in connection with the platform, means separately 50 supporting the plate from the shaft and means between the shaft and one of said supporting means to effect vertical movement of the plate by rotation of the shaft.

JOHN M. BETTENCOURT. 55
